UNITED STATES PATENT OFFICE.

FREDERICK H. STARLING, OF PHILADELPHIA, PENNSYLVANIA.

DESIGN FOR A SHOW-CASE.

SPECIFICATION forming part of Design No. 19,571, registered January 7, 1890.

Application filed December 13, 1889. Serial No. 333,690. Term of patent 7 years.

To all whom it may concern:

Be it known that I, FREDERICK H. STARLING, a citizen of the United States, residing in the city and county of Philadelphia, and State of Pennsylvania, have invented and produced a new and original Design for Show-Cases, of which the following is a specification, reference being had to the accompanying drawings, forming a part thereof.

10 My invention relates to a design for showcases, the object being to provide a case of the double upright class of attractive and graceful appearance.

15 The drawing shows a perspective view of a show-case embodying my design, in which A represents the central part of the case, with flat top B and curved front C.

D D represent the upright sides of the case,

consisting of flat tops d, flat inner side sections e, flat front portions f, and curved front 20 portions g.

The essential feature of my design consists in the flat front portions f, the flat inner side sections e, and the curved front portions g. It will be observed that the sections g are bent 25 to form curved lines from the points x to the points x', where said sections join the flat sections e and f, thus presenting to the eye an attractive and finished appearance.

I claim—

30 The design for a show-case, substantially as herein shown and described.

FREDERICK H. STARLING.

In presence of—

HOWARD A. SNYDER,
SAMUEL BEAL.
